UNITED STATES PATENT OFFICE.

BENJAMIN F. WOODING, OF MONTCLAIR, NEW JERSEY.

CIRCUIT CONTROLLER.

Application filed June 11, 1927, Serial No. 198,047. Renewed May 21, 1929.

The present invention relates to magnetically operated and controlled circuit controllers, and particularly to circuit controllers of this character that are adapted to be carried by a vehicle and operated inductively by a magnet located on the roadway, for the purpose of controlling the vehicle either by giving an alarm thereon or by initiating the operation of mechanism for stopping the vehicle or by doing both. The circuit controller of the present invention may for example be used in the train controlling system shown and described in my copending application Serial No. 59,869, filed Oct. 1, 1925, or in the automobile controlling system disclosed in my copending application Serial No. 72,772, filed Dec. 2, 1925. The circuit controller may be found useful in other relations and for other purposes, and it is intended in the present application to claim the controller per se without reference to any specific system or use to which it may be applied.

The specific nature of the invention and particular objects thereof will be described hereinafter and the novel features will be pointed out in the claims.

Referring to the accompanying drawings: Fig. 1 is a diagrammatic view illustrating an application of the invention to automatic train control;

Fig. 2 is a longitudinal vertical section through the circuit controller; and

Fig. 3 is a horizontal sectional view.

Referring first to Figs. 2 and 3, the elements of the circuit controller are housed in an oblong box, designated generally by the reference character A. This box consists of an oblong rectangular body 10 which may be formed of a single piece of non-magnetic metal or of a suitable composition. The open ends of body 10 are closed by flanged caps 12 and 13, which are tightly secured on said ends so as to effect substantially hermetically sealed closures, these caps being also composed of non-magnetic material.

Supported centrally in the box is a bar 14 of wood or other suitable insulating material connected by brackets 15 to a wooden strip 16 which fits under the top of the box. A thin strip 17 of soft iron is screw clamped at its outer end between metal plates 18 and 19, plate 19 resting on bar 14 and plate 18 being integral with a binding post 20 which extends through an insulating bushing in cap 12. Similarly, a thin strip 21 of soft iron is clamped at its outer end between plates 22

and 23, plate 22 being integral with a binding post 24 which extends through an insulating bushing in cap 13. These magnetic strips are supported medially on metal pieces 25 screwed to the top of bar 14, and the inner free ends of said strips slightly overlap. Attached to the upper face of strip 21 is a flexible piece of metal 26 which projects over the end portion of strip 17 and carries a button 27 of non-magnetic metal which normally engages a similar button 28 secured to strip 17.

Mounted in a central aperture in bar 14 is an electro-magnet 29 having a core which projects slightly above bar 14 under the end portion of strip 21. This electro-magnet has a lead 30 connected to binding post 31 mounted in an insulating bushing 32 in an aperture of cap 12, and the other lead 33 of the magnet is connected to a similar binding post 34 in cap 13.

A permanent bar magnet 35 rests on the bottom of box A and extends from end to end of the box. Flux from this permanent magnet passes longitudinally through the magnetic strips 17 and 21 and normally holds the ends of these strips engaged, a thin insulating film or strip being interposed between the engaging surfaces.

Referring now to Fig. 1, which illustrates an application of the circuit controller above described to a train control system: Two circuit controllers A may be used mounted at convenient points under a locomotive or a tender, one controller being operative when the locomotive is going ahead and the other controller being operative when the locomotive is backing. As shown, the right hand controller A is operative and the left hand controller inoperative. The circuit of a suitable electro-magnetic valve 36 is as follows: battery B, conductor 37, valve 36, conductors 38 and 39, binding post 20, magnetic strips 17 and 21, binding post 24, conductor 40, an insulated segment 41, a slotted arm 42 engaging said segment, and conductor 43 back to battery B. The electro-magnetic valve 36 is adapted to give an alarm or to apply the brakes, or both, when its circuit is interrupted. The slotted arm 42 is pivoted at 44, the center of the circle defined by segments 41, 45 and 46, and is connected by a link 47 to the reversing lever 48 of the locomotive. During normal running of the locomotive, lever 48 is in the position shown, and arm 42 engages segment 41, closing the circuit of valve 46 through the right hand controller A, this

circuit being the one just traced. When the locomotive is reversed lever 48 is moved towards the left moving arm 42 from segment 41 to segment 45. The circuit through the 5 right hand controller A is thereby broken, but another circuit is formed through the electro- 10 magnetic valve 36 by way of the left hand controller A, as follows: battery B, conductor 37, valve 36, conductors 38 and 49, the 15 magnetic strips 21 and 17 of the left hand controller, conductor 50, segment 45, arm 42 and conductor 43 back to battery. This last 20 circuit is closed before the circuit first traced is opened, so that there is no interruption in the energization of valve 36 when the reversing lever 48 is operated. If the connecting link 47 between lever 48 and lever 42 should be broken, lever 42 would drop by gravity and engage the insulated segment 46, opening 25 the circuit of valve 36, rendering the failure on the side of safety.

When the circuit controller is used in a train control system, the track system will include induction means, such as permanent 25 magnets located in the roadway, adapted to coact with the circuit controllers on the locomotive and to operate said circuit controllers under danger or caution conditions to interrupt the circuit of the train controlling 30 electro-magnetic valve 36. Normally the soft iron strips 17 and 21 have their ends held engaged by the flux from the permanent magnet 35, but when the controller is carried over a magnet on the track the flux of 35 which is opposed in direction to that of the controller magnet 35, the action of the latter magnet is neutralized and strip 21 springs up out of engagement with strip 17, opening the circuit of electro-magnetic valve 36. 40 After the controller passes out of the influence of the magnet on the track, the end of strip 21 remains up out of engagement with strip 17, for although the permanent magnet 33 is strong enough to hold these strips in 45 engagement when once they have been brought into engagement, it is not strong enough to bring the strips into engagement from their open position. For reengaging the strips, therefore, after they have been 50 opened, I provide the resetting electro-magnet 29, which must be energized by a manual operation of the engineer or driver of the vehicle in order to reclose the circuit opened by the controller. In Fig. 1 the resetting circuit is from a battery B', conductor 51, push button 52, conductor 53, binding post 54 of the right hand controller, lead 33, the winding of magnet 29, lead 30, binding post 31, conductor 55, through similar elements of 55 the left hand controller, conductor 56, and push button 57. The push buttons 52 and 57 may be located at points so as to require the cooperation of two persons, for example, the engineer and the conductor, in order to 60 reset the controller.

The function of the resilient strip 26 and the contact buttons 27 and 28 is to hold closed the circuit through the controller in spite of any slight momentary disengagements of the ends of strips 17 and 21, caused, for example, by jarring and jolting of the vehicle. For this purpose the strip 26 is constructed and biased so that it tends to hold engagement between buttons 27 and 28 during slight separations of the ends of strips 17 and 21, 70 so that the circuit through the controller will not be opened intermittently because of slight separations of the ends of the strips, but will only be opened when the end of strip 21 moves up a substantial distance from the 75 end of strip 17 on the passage of the controller over an induction means in the roadway. The contact buttons 27 and 28 are formed of some non-magnetic metal so that they will not tend to adhere magnetically. 80 85

For some uses it is desirable to have the circuit controller normally maintain closed a circuit, as has been described, and also to close a circuit when this normally closed circuit is opened. For example, where the controller is used on an automobile to control the automobile when approaching grade crossings or other intersections, it is desirable to have the controller maintain a closed contact in the ignition circuit and to have it 90 close an alarm circuit when the ignition circuit is opened. I have therefore illustrated in Fig. 2 a contact 60 which is adapted to engage contact button 27 upon disengagement of strips 17 and 21 and buttons 27 and 28. 95 The circuit through contact 60 may include an alarm while that through strips 17 and 21 may be the ignition circuit. 100

Now having described my invention without intending to limit the scope thereof except as defined in the claims, what I claim as new and desire to secure by Letters Patent of the United States is:—

1. A circuit controlling unit adapted to be operated inductively, comprising two thin 110 spring plates of magnetic material mounted in alignment with their ends overlapping and tending to spring apart, and a magnet mounted in proximity to said plates so that the flux thereof passes thru said plates and normally 115 holds their ends engaged.

2. A circuit controlling unit comprising two thin spring plates of magnetic material mounted in alignment with their ends overlapping and tending to spring apart, and a 120 permanent bar magnet mounted parallel to said plates operating normally to hold said ends engaged.

3. A circuit controlling unit comprising a box of nonmagnetic material, two thin plates 125 of magnetic material mounted in said box with their ends overlapping and tending to spring apart, said plates forming part of an electric circuit, a magnet mounted in proximity to said plates normally holding said 130

ends engaged, the strength of said magnet being insufficient to bring said plates into engagement from their separated position, and means to move said plates into engagement from such position.

4. A circuit controlling unit adapted to be operated inductively, comprising a housing formed of non-magnetic material, two thin strips of soft iron supported in said housing and having overlapping ends, one of said strips being resilient and tending to spring away from the other strip, a permanent magnet in the housing mounted so that the flux therefrom flows through said strips and normally holds them engaged, said flux being insufficient to bring the strips into engagement from their separated position, and an electro-magnet in the housing adapted when energized to bring the strips into engagement.

5. A circuit controller comprising an elongated housing of non-magnetic material, a bar of insulating material supported in the housing, two thin strips of soft iron secured at their outer ends to the top of said bar, a binding post extending through each end of the housing and connected to the respective strip, one of said strips being resilient and tending to spring away from the other strip, an electromagnet mounted in an aperture in said bar of insulating material and having a pole projecting under one of said strips, and a permanent bar magnet resting on the bottom of the housing.

35 6. In an automatic vehicle controlling system, a circuit controlling unit adapted to be mounted on a vehicle so as to be operated inductively by magnets in the roadway, comprising a box of non-magnetic material, two thin spring plates of magnetic material mounted in said box with their ends overlapping, and a magnet mounted in proximity to said plates, the overlapping ends of said plates tending to spring apart and said magnet operating normally to hold said ends engaged.

7. In an automatic vehicle controlling system, a circuit controlling unit comprising two thin spring plates of magnetic material adapted to be mounted on a vehicle for coaction with magnets on the roadway, said plates having overlapping ends and one of said plates being biased to move out of engagement with the other, and a permanent magnet mounted substantially parallel to said plates and operating normally to hold said plates engaged.

8. In an automatic vehicle controlling system, a circuit controlling unit comprising two thin plates of magnetic material adapted to be mounted on a vehicle for coaction with magnets on the roadway, said plates having overlapping ends and one of said plates being biased to move out of engagement with the other, a light flexible strip secured to one of

said plates and having its free end engaging the other plate, and a permanent bar magnet mounted in proximity to said plates so that the flux thereof operates normally to hold said plates engaged.

70 9. In an automatic vehicle controlling system, a circuit controlling unit comprising two thin plates of magnetic material adapted to be mounted on a vehicle for coaction with magnets on the roadway, said plates having overlapping ends and one plate being resilient and tending to move out of engagement with the other, a light flexible strip secured to one plate and having its free end engaging a non-magnetic contact on the other plate, and a permanent bar magnet mounted parallel to said plates and operating normally to hold said plates engaged.

10. In an automatic vehicle controlling system, a circuit controller comprising two thin plates of magnetic material adapted to be mounted on a vehicle for coaction with magnets on the roadway, said plates having overlapping ends and one plate being resilient and tending to spring away from the other plate, a permanent bar magnet mounted parallel to said plates and operating normally to hold said plates engaged but being ineffective to bring said plates into engagement from their separated positions, an electro-magnet adapted to bring said plates into engagement, and a circuit for said electro-magnet comprising a plurality of normally open manually operable contacts in series.

95 11. In an automatic train control system, a circuit controlling unit adapted to be secured to a vehicle for coaction with track magnets, comprising a box of non-magnetic material, two thin plates of magnetic material mounted in said box with their ends overlapping, and a magnet mounted over said plates, the overlapping ends of said plates tending to spring apart and said magnet operating normally to hold said ends engaged.

105 12. In an automatic train control system, a circuit controlling unit comprising two thin plates of magnetic material adapted to be mounted on a vehicle for coaction with track magnets, said plates having overlapping ends and one of said plates being biased to move out of engagement with the other, and a magnet mounted over said plates substantially parallel therewith and operating normally to hold said plates engaged.

115 13. In an automatic train control system, a circuit controlling unit comprising two thin plates of magnetic material adapted to be mounted on a vehicle for coaction with track magnets, said plates having overlapping ends and one of said plates being biased to move out of engagement with the other, a light flexible strip secured to one of said plates and having its free end engaging the other plate, and a magnet mounted over said

plates substantially parallel therewith and operating normally to hold said plates engaged.

14. In an automatic train control system, 5 a circuit controlling unit comprising two thin plates of magnetic material adapted to be mounted on a vehicle for coaction with track magnets, said plates having overlapping ends and one plate being resilient and 10 tending to move out of engagement with the other and having a large area whereby its movements are sluggish, a light flexible strip secured to one plate and having its free end engaging a non-magnetic contact 15 on the other plate, and a permanent magnet mounted over said plates substantially parallel therewith and operating normally to hold said plates engaged.

15. In an automatic train control system, 20 a circuit controlling unit adapted to be secured to a vehicle for coaction with track magnets, comprising a box of non-magnetic material, two thin plates of magnetic material mounted in said box having overlapping 25 ends, binding screws passing through the top of the box and engaging the other ends of said plates to clamp them against longitudinal displacement, and a permanent magnet mounted above the box substantially 30 parallel to the plates, the overlapping ends of said plates tending to spring apart and said magnet operating normally to hold said ends engaged.

16. In an automatic train control system, 35 a circuit controlling unit adapted to be secured to a vehicle for coaction with track magnets, comprising a shallow oblong box of non-magnetic material, two thin plates of magnetic material resting on the bottom of 40 said box and loosely fitting the sides thereof, the inner ends of said plates slightly overlapping, the overlapping ends of said plates tending to spring apart, and a permanent magnet operating normally to hold 45 said plates engaged.

17. In an automatic train control system, a circuit controlling unit adapted to be secured to a vehicle for coaction with track

magnets, comprising a shallow oblong box 50 of non-magnetic material, two thin plates of magnetic material resting on the bottom of said box and having their inner ends slightly overlapping, binding posts passing through the top of the box engaging the outer ends 55 of said plates to clamp them against longitudinal displacement, a light flexible strip secured to one of said plates and extending over the other plate and engaging therewith, the overlapping ends of said plates tending to spring apart, and a permanent magnet 60 mounted above said box operating normally to hold said plates engaged.

18. A circuit controlling unit adapted to be operated inductively, comprising two thin plates of magnetic material mounted in 65 alignment with their ends overlapping and biased to spring apart, and a magnet mounted in proximity to said plates normally holding said ends engaged.

19. A circuit controlling unit comprising 70 two thin plates of magnetic material mounted in alignment with their ends overlapping and tending to spring apart, and a permanent magnet mounted parallel to said plates operating normally to hold said ends 75 engaged.

20. A circuit controlling unit comprising a box of non-magnetic material, two thin plates of magnetic material mounted in said 80 box with their ends overlapping and tending to spring apart, said plates forming part of an electric circuit, and a magnet mounted over said plates normally holding said ends engaged.

21. A circuit controlling unit comprising 85 a box of non-magnetic material, two thin plates of magnetic material mounted in said box with their ends overlapping and tending to spring apart, said plates forming part of an electric circuit, and a permanent magnet 90 mounted in proximity to said plates operating normally to hold said ends engaged.

In testimony whereof I hereunto affix my signature.

BENJAMIN F. WOODING.
